UNITED STATES PATENT OFFICE.

CHARLES C. HANSEN, OF EASTON, PENNSYLVANIA, ASSIGNOR TO INGERSOLL-RAND COMPANY, OF JERSEY CITY, NEW JERSEY, A CORPORATION OF NEW JERSEY.

LUBRICATOR.

Application filed October 30, 1926. Serial No. 145,249.

This invention relates to oiling devices, but more particularly to an oiling device which may be connected to a pressure fluid supply line for the purpose of supplying oil to fluid actuated machines, such as rock drills, pneumatic hoists, and the like.

One object of the invention is to deliver lubricant in suitable quantities to fluid actuated engines through the medium of the pressure fluid utilized for actuating such engines.

Further objects will be in part obvious and in part pointed out hereinafter.

The invention consists of the features of construction and combination of elements substantially as hereinafter described and more particularly pointed out in the appended claims and illustrated in the accompanying drawings, in which

Figure 1 is a longitudinal sectional elevation of an oiling device,

Figure 2 is a sectional elevation taken through Figure 1 on the line 2—2 looking in the direction of the arrows.

Figure 3 is a plan view of the central core of Fig. 2 taken on the line 3—3 looking in the direction of the arrows,

Figure 4 is an elevation of the central core of Fig. 1, partly in section,

Figure 5 is a plan view of Fig. 4 looking down on the top,

Figure 6 is a sectional elevation of Fig. 4 taken on the line 6—6 looking in the direction of the arrows, and

Figure 7 is a plan view of Fig. 4 looking up from the bottom.

Referring to the drawings the invention comprises a casing A having a wall B which divides the casing into an oil reservoir C and a fluid passageway D. The fluid passageway in this instance is threaded at its ends as at E for the reception of the ends of suitable conduits F and G which may lead from a source of pressure fluid supply for delivering pressure fluid to a fluid actuated engine or engines, such as rock drills, pneumatic tools, and motor hoists.

A vent J between the oil reservoir C and the fluid passageway D admits pressure fluid to the oil chamber C. Means for delivering oil from the reservoir C into the passageway D is provided in the form of the member H preferably of general cylindrical formation inserted in the wall B and extending into the reservoir C and the passageway D.

During the operation of the engine which

is supplied with motive fluid passing through the passage D oil passes through the screen L into the chamber K. Two pulley sheaves O and P are mounted on shafts Q and R respectively and a continuous bead chain S passes over the sheaves O and P. A propeller T fixed to the shaft R is caused to rotate by the pressure fluid moving at considerable velocity through the passageway D. The continuous motion of the chain S through the oil in the chamber K carries oil by adhesion into the moving current of pressure fluid where it is blown from the chain and carried by the pressure fluid to the engine in which it is required.

A preferred construction of the device is shown in the drawings. The oil being supplied to the reservoir by removing the plug U. The member H may be removed when desired by removing the cap V which is screwed into the chamber A.

I claim:

1. An oiling device comprising a casing having a wall dividing said casing into an oil reservoir and a stationary pressure fluid passageway, a member extending through said wall into the passageway and into the reservoir, said member having pulley sheaves in the passageway and in the reservoir, said pulley in the passageway having a propeller mounted thereon, the axis of said propeller parallel to the axis of said pressure fluid passageway, and a continuous flexible member passing over said pulleys into the oil and into the passageway.

2. An oiling device comprising a casing having a wall dividing said casing into an oil reservoir and a stationary pressure fluid passageway, a member extending through said wall into the passageway and into the reservoir, said member having pulley sheaves in the passageway and in the reservoir, said pulley in the passageway having a propeller mounted thereon, the axis of said propeller parallel to the axis of said pressure fluid passageway and a continuous chain passing over said pulleys into the oil and into the passageway.

3. An oiling device comprising a casing having a wall dividing said casing into an oil reservoir and a stationary pressure fluid passageway, a member extending through said wall into the passageway and into the reservoir, the end of the said member in the said reservoir being covered by a porous

screen, said member having pulley sheaves in the passageway and in the reservoir, said pulley in the passageway having a propeller mounted thereon, the axis of said propeller parallel to the axis of said pressure fluid passageway, and a continuous chain passing over said pulleys into the oil and into the passageway and adapted to carry oil substantially to the center of said pressure fluid passageway.

4. An oiling device comprising a casing having a wall dividing said casing into an oil reservoir and a stationary pressure fluid passageway, a member extending through said wall into the passageway and into the

reservoir, the end of the said member in the said reservoir being covered by a porous screen, said member having pulley sheaves in the passageway and in the reservoir, said pulley in the passageway having a propeller mounted thereon, and a continuous chain passing over said pulleys into the oil and into the passageway and adapted to carry oil substantially to the center of the pressure fluid passageway without bringing said oil into contact with the side walls of said pressure fluid passageway.

In testimony whereof I have signed this specification.

CHARLES C. HANSEN.
